HANGER FOR USE ON A SHOWER PIPE

Franklin S. Briles, Rolling Hills, Calif., assignor to Franklin S. Briles, Inc., El Segundo, Calif., a corporation of California

Filed Mar. 17, 1965, Ser. No. 84,308

Term of patent 14 years

(Cl. D4—3)

FIG. 1.

FIG. 2.

FIG. 3.

FIG. 4.

I claim:

The ornamental design for a hanger for use on a shower pipe, as shown.
